Inventor:
Warren J. Parsons,
by Franks, Appelmay,

UNITED STATES PATENT OFFICE.

WARREN J. PARSONS, OF HUNTINGTON, WEST VIRGINIA.

CHAIR.

1,314,830.

Specification of Letters Patent.

Patented Sept. 2, 1919.

Application filed November 1, 1918, Serial No. 260,704. Renewed July 11, 1919. Serial No. 310,203.

To all whom it may concern:

Be it known that I, WARREN J. PARSONS, a citizen of the United States of America, and resident of Huntington, in the county of 5 Cabell and State of West Virginia, have invented certain new and useful Improvements in Chairs, of which the following is a specification.

This invention relates to chairs and particularly to collapsible or foldable chairs, the said invention having for its object the provision of novel means whereby a back and supporting portion are formed in a single piece of material, novel means being provided for detachably securing a seat in operative position, yet permitting the said seat to be displaced so that it may be nested or folded with respect to the back to occupy comparatively little space when so folded, 15 the said invention further including a brace or leg hingedly or detachably connected to a member adapted for holding the seat in operative position.

A chair made in accordance with this invention will be found of great utility in a great number of places, as for instance, on steamboats, at ball games, picnics, in undertakers' operations and in fact wherever it is desired to provide temporary seating capacity with the idea of removing the seats thereafter.

A further object of this invention is to provide a chair comprising few metallic parts, said chair being strong and durable, 35 as well as efficient and satisfactory in use.

With the foregoing and other objects in view, the invention consists in the details of construction, and in the arrangement and combination of parts to be hereinafter more 40 fully set forth and claimed.

In describing the invention in detail, reference will be had to the accompanying drawings forming part of this specification wherein like characters denote corresponding parts in the several views, and in which—

Figure 1 illustrates a view in side elevation;

Fig. 2 illustrates a view in front elevation;

Fig. 3 illustrates a view in side elevation with the parts nested;

Fig. 4 illustrates a detail view of the back member;

Fig. 5 illustrates a detail view of the leg

or brace, which may also be constructed with 55 a double base like Fig. 4; and

Fig. 6 illustrates a detail view of the seat. In these drawings a combined back and support or legs is formed of a single piece of material, said member having a transversely 60 disposed slot 10 between the back 11 and the support or legs 12 and if desired, the said back may have an aperture 13 to facilitate manipulation, the hand or arm may be inserted in the opening to afford a hand grasp 65 or arm hold.

The seat 14 has a tongue 15 adapted to be inserted in the slot 10 when the seat is in operative position as shown in Fig. 1 and the seat is therefore anchored or supported 70 at one point through the instrumentality of the tongue which bears against the edge of the slot, which edge constitutes its support. The seat is further provided with clips 16 and 17 which retain a bail or hanger 18 in 75 operative relation with the seat so that the hanger may support the seat in approximately a horizontal position, yet permitting the said seat to be swung from the said approximately horizontal position to a position 80 parallel with the back, it being understood that the bail or hanger is swingingly or pivotally mounted in clips 19 and 20 attached in any suitable way to the back 11.

The leg, brace or prop 21 has a plate 22 85 secured to it by the fastenings 23, and the said plate projects beyond the end of the member 21 and forms a flange which is inserted between the bail or support 18 and the back, so that the said bail or support 90 bears against the end of the member 21 and prevents rearward tilting of the chair. A stay chain or strap 24 has its ends connected to the member 21 and the member 12 respectively, so that the outward swing or movement of one with relation to the other beyond a predetermined point is obviated. The tongue 15 forces 21, which may have a double base like 12, into place.

A chair made in accordance with the foregoing invention can be produced without the exercise of undue skill and therefore can be manufactured cheaply and can be folded compactly when not in use. The members shown in Figs. 4, 5 and 6 may be constructed 105 of metal as well as of wood.

The bail or hanger 18 preferably comprises a single strap of metal bent substan-

tially rectangular, the sides being in engagement with the seat and back respectively and the ends extending from the back to the seat and if desired, the ends may be curved outwardly to afford a greater clearance than would be afforded were the ends straight, so as to accommodate itself to large or small persons.

The rear part of the seat or tongue 15 when inserted in the slot 10, in unfolding the chair, automatically pushes the brace or prop 21 into proper position and serves as a brace to hold it there so long as the chair is in use or unfolded. The brace or prop 21 15 may be constructed either with a single base or with a double base like the member 12.

I claim—

1. In a chair, a member comprising a back and a support, said member having a transversely disposed slot intermediate its length, 20 a seat having a tongue insertible in the slot whereby one end of the seat is supported, a hanger extending under the seat at a point distant from the first mentioned member, 25 and means for attaching the hanger to the back.

2. In a chair, a member comprising a back, and a support, said member having a transversely disposed slot intermediate its length, 30 a seat having a tongue insertible in the slot whereby one end of the seat is supported, a hanger extending under the seat at a point distant from the first mentioned member, 35 means for attaching the hanger to the back, and a brace against which the hanger bears.

3. In a chair, a member comprising a back and a support, said member having a transversely disposed slot intermediate its length, a seat having a tongue insertible in the slot

whereby one end of the seat is supported, a 40 hanger extending under the seat at a point distant from the first mentioned member, means for attaching the hanger to the back, a brace against which the hanger bears, and a plate connected to the brace and extending 45 between the hanger and back.

4. In a chair, a member comprising a back and support, said member having a transversely disposed slot intermediate its length, 50 a seat having a tongue insertible in the slot whereby one end of the seat is supported, a hanger extending under the seat at a point distant from the first mentioned member, means for attaching the hanger to the back, and a brace hingedly connected to the back, 55 against which the hanger bears.

5. In a chair, a member comprising a back and support, said member having a transversely disposed slot intermediate its length, 60 a seat having a tongue insertible in the slot whereby one end of the seat is supported and by which the brace or prop is automatically forced into position when the chair is unfolded for use, a hanger extending under the seat at a point in front of and distant 65 from the first mentioned member whereby the forward end of the seat is supported, means for attaching the hanger to the back, a brace hingedly connected to the back against which the hanger bears, and a stay 70 chain or strap attached to the support and the brace or prop and of such a length as to prevent the support and the brace from separating beyond a predetermined distance and so as to afford to the chair the greatest degree 75 of stability and equilibrium.

WARREN J. PARSONS.
